UNITED STATES PATENT OFFICE.

HOWARD M. PERKINS, OF MERIDEN, CONNECTICUT, ASSIGNOR TO REMO MANUFACTURING COMPANY, OF MERIDEN, CONNECTICUT, A CORPORATION OF CONNECTICUT.

LAUNDRY-MARKING PIN.

Application filed June 16, 1926. Serial No. 116,385.

This invention relates to identification devices, and more particularly to a safety marking pin for use in laundries, factories, offices, etc.

5 One object of this invention is to provide a marking pin of the above nature which may be attached to an article to be identified and which is adapted to be hung on a rod together with other similar pins.

10 A further object is to provide a pin of the above nature having a relatively large marking plate secured thereto, said plate having no sharp edges which might injure the garment or other article to which it is attached.

15 A further object is to provide a device of the above nature which will be simple in construction, inexpensive to manufacture, easy to manipulate, compact, ornamental in appearance, and very efficient and durable 20 in use.

With these and other objects in view there has been illustrated on the accompanying drawings one form in which the invention may be conveniently embodied in practice.

25 Fig. 1 represents a top plan view of the pin, as it appears with the point protected by the guard member.

30 Fig. 2 is a bottom plan view of the same, as it appears in open position with the pin unprotected by the guard member.

35 Fig. 3 is a transverse sectional view of the plate end of the pin, taken along the line 3—3 of Fig. 1, looking in the direction of the arrows.

40 Referring now to the drawings in which like reference numerals denote corresponding parts throughout the several views, the numeral 10 indicates the pointed leg of the pin, said pin being preferably constructed from a single piece of wire bent upon itself into substantially U-shape and having a 45 semi-circular enlarged intermediate section 11. The end 12 of said wire opposite from the point is adapted to lie substantially parallel with the pointed end 10 when the marking pin is in closed position, as shown in Fig. 1. When the marking pin is open, however, the ends of the pin slightly diverge from each other, as shown in Fig. 2.

50 In order to protect the pointed end 10 of the marking pin, a sheet metal guard member 13 is provided, said member 13 being bent into substantially semi-circular shape and adapted to be secured in any suitable

manner, as by solder, to a curved extremity 55 16 of the pin end 12, as clearly shown in Figs. 1 and 2. The guard member has the usual entering slots 14 and 15 in its opposite faces to permit the pointed end of the pin to be inserted in the guard member from 60 either side thereof.

In order to permit the rapid identification of the article to which the pin is attached, provision is made of a relatively 65 large marking plate 17, said marking plate being semi-circular at its outer end and substantially rectangular at its inner end. The marking plate 17 is provided throughout its outer periphery with a downwardly extending flange 18, said flange being 70 adapted to be bent or curled over the wire of the intermediate section 11 of the pin in order to securely lock said plate in position. The marking plate 17 may be provided on its top face with a suitable identifying inscription, herein disclosed as three 75 raised figures representing the number "500".

The rectangular end of the marking plate 17 is provided with a straight transverse inner edge 19, said edge having a flange 20 80 curled over downwardly upon itself, to prevent a garment from being torn in case it should happen to become wedged between said plate 17 and the parallel sides 21 and 22 of the wire which extend for a considerable 85 distance out of the marker plate leaving a relatively large space at the center of the pin. This construction not only permits the marking pin to be readily slipped over the suspending rods, not shown, but 90 also allows relatively thick articles to be engaged by the marking pin. The enlarged parallel sides 21 and 22 of the intermediate section of the pin are joined to the ends 95 10 and 12 thereof by means of a pair of converging sections 23 and 24.

One advantage of the present invention is that the marking pin may be made extremely thin and consequently will readily 100 pass through mangles or other laundry machines without injury.

While there has been disclosed in this specification one form in which the invention may be embodied, it is to be understood that this form is shown for the purpose of illustration only, and that the invention is not to be limited to the specific disclosure but may be modified and embodied 105

in various other forms without departing from its spirit. In short, the invention includes all the modifications and embodiments coming within the scope of the following claims.

Having thus fully described the invention, what is claimed as new, and for which it is desired to secure Letters Patent, is:

1. In a safety marking pin, a looped wire having a rounded intermediate section with its sides spaced relatively far apart, the ends of said looped wire being relatively near together, converging inclined sections for connecting said sides with said ends, and a symmetrical marking plate having a flange curled about said sides and said rounded intermediate section, said plate having a transverse interior edge curled upon itself and terminating short of said inclined sections to provide a relatively large open

space within the pin and prevent tearing of the clothes by said plate.

2. In a safety marking pin, a looped wire having a rounded intermediate section with parallel sides spaced relatively far apart, the ends of said looped wire being parallel and relatively near together, converging inclined sections for connecting said sides with said ends, and a symmetrical marking plate having a flange curled about said sides and said rounded intermediate section, said plate having a transverse interior edge curled upon itself and terminating short of said inclined sections to provide a relatively large open space within the pin and prevent tearing of the clothes by said plate.

In testimony whereof, I have affixed my signature to this specification.

HOWARD M. PERKINS.
